HOOK FASTENER

Charles L. Sheldon, Watertown, Mass., assignor
to Hood Rubber Company, Inc., Watertown,
Mass., a corporation of Delaware

Application December 5, 1934, Serial No. 756,079

2 Claims. (Cl. 24—226)

This invention relates to hook fasteners and is particularly useful in the manufacture of shoes or other articles of apparel and the like.

The principal objects of the invention are to provide security, simplicity and efficiency of operation in a fastener device, and to provide against accidental injury to the catch element thereof.

Other objects will appear from the following description and the accompanying drawing.

Of the drawing:

Fig. 1 is a perspective view of the fastener catch in its preferred form.

Fig. 2 is a plan view of the catch as applied to a shoe part, part of the shoe strap, which carries the hook element, being also shown and part broken away so as to show only the catch of the fastener.

Fig. 3 is a sectional view taken on line 3—3 of Fig. 2.

Fig. 4 is a sectional view taken on line 4—4 of Fig. 2, but including the end of the strap and the hook member attached thereto.

Referring to the drawing, the catch member is designated by the numeral 10 and in its preferred form comprises a single piece of sheet metal, folded upon itself to provide a flat attaching base 11, having a single rivet opening 12, and a pair of spurs 13, 13', for holding it against rotative movement, and, spaced therefrom, a horse-shoe shaped catch element 14 or loop for engaging the hook. An integral lug 15 turned down from the catch element and impinging against the attaching base, serves as a prop to hold the catch in spaced relation to the base against accidentally applied forces tending to flatten the catch.

The hook member 16 is the same as the hook member of the patent of Frederic C. Hood No. 1,787,728, issued January 6, 1931, and comprises a plate 17 formed with a centrally located projecting hook 18 and a pair of slotted openings 19, 19' through which the strap 20 is laced.

The catch member comprising the subject matter of the present application insures sufficient space for the hook to enter at all times, said space not being affected by bending of the material to which the catch is attached, as when the material is curved around the instep of a foot. The use of only one rivet limits weakening of the material, to which the catch is applied, to a minimum.

I claim:

1. A catch for engaging a hook fastener, said catch comprising a single piece of metal formed to provide a flat base member, a hook-engaging loop member extending along said base and spaced therefrom, and a lug formed on one of said members and extending toward the other and impinging thereagainst for holding said members in spaced relation said base member being directly beneath said loop member so as to be concealed thereby.

2. A catch for engaging a hook fastener, said catch comprising a single piece of sheet metal formed to provide a flat base member having a central rivet opening and a garment engaging spur, a hook-engaging loop member integral therewith and extending over said base in spaced relation thereto, and a marginal wall integral with one of said members and located between the members for holding them in spaced relation.

CHARLES L. SHELDON.
